UNITED STATES PATENT OFFICE.

LISLE BERGERON, OF SIOUX CITY, IOWA, ASSIGNOR TO JOHNSON BISCUIT COMPANY, OF SIOUX CITY, IOWA, A CORPORATION OF IOWA.

DESIGN FOR A CANDY PIECE.

54,717.

Specification for Design.

Patented Mar. 23, 1920.

Application filed May 29, 1919. Serial No. 300,740. Term of patent 14 years.

To all whom it may concern:

Be it known that I, LISLE BERGERON, a citizen of the United States, and a resident of Sioux City, in the county of Woodbury and State of Iowa, have invented a new, original, and ornamental Design for Candy Pieces, of which the following is a specification, reference being had to the accompanying drawing, forming a part thereof.

The figure is a perspective view of a candy piece showing my new design.

I claim;

The ornamental design for a candy piece as shown.

LISLE BERGERON.
